WITNESS:

ALFRED HERSCHEL
INVENTOR
BY Victor J. Evans
ATTORNEY

UNITED STATES PATENT OFFICE.

ALFRED HERSCHEL, OF NEW YORK, N. Y.

RADIO LOUD-SPEAKER.

Application filed July 25, 1927. Serial No. 208,331.

This invention relates to improvements in radio loud speakers and has particular reference to a mounting for sound producing units thereof.

5 The primary object of the invention resides in a means by which the sound qualities of a loud speaker are improved by reason of the non-vibratory base on which the armature or flapper is mounted. Heretofore, the vibration of the unit mounting has interfered with the quality of sound produced which prevents reproduction of a natural tone.

Another object of the invention is to provide a mounting for loud speaker units in 15 which the anchorage for the armature or flapper is embedded in a base of non-sounding metal.

With these and other objects in view, the invention resides in certain novel construction and combination and arrangement of parts, the essential features of which are hereinafter fully described, are particularly pointed out in the appended claims, and are illustrated in the accompanying drawing, in 25 which:—

Figure 1 is a front elevation of my improved loud speaker unit mounting.

Figure 2 is a vertical sectional view on the line 2—2 of Figure 1.

30 Figure 3 is a similar view on the line 3—3 of Figure 1.

Figure 4 is a detail vertical sectional view on the line 4—4 of Figure 3.

Figure 5 is a detail vertical sectional view 35 of a modified form.

Referring more particularly to the drawing, the reference numeral 10 designates a disk or base made of lead having a proportionate amount of antimony mixed therewith 40 to slightly harden the same. The front face of the base has a projecting boss 11 thereon within which an elongated anchor plate 12 is embedded. A metal collar 13 is also embedded in the boss and has one end bearing 45 against the anchor plate 12 and its other end flush with the outer face of the boss. The loud speaker armature or flexible flapper is indicated at 14 and has one of its ends fastened to the anchor plate by a screw 15 which threads into an opening 16 in the anchor plate 12. The screw also passes through one end of a guide 17 which overlies the armature but which has its free end offset as at 18 and provided with an opening 19 for the passage of

the vibratory pin 20 which has one of its ends 55 fixed to the armature and its other end fixed to the apex of a cone diaphragm 21.

The base casting 10 has an opening 22 therein for register with a threaded opening 23 in the anchor plate and with which the 60 threaded end of an adjusting screw 24 co-acts. The screw 24 is adapted to bear against the armature 14 to apply pressure thereon for adjusting the range of movement of the same for adapting the unit for operation under 65 various conditions. The guide 17 has a teet 25 thereon for bearing engagement with the armature at a point opposite the adjusting screw and which tends to space the major portion of the guide from the armature. 70

In Figure 5 of the drawing, I have shown a slightly modified form of my invention, in which the numeral 10' designates a portion of the lead base in which spaced internally threaded sleeves 12' and 12'' are embedded, 75 the same having heads 26 for anchorage purposes. The outer ends of the sleeves lie flush with the front of the base 10' and threadedly receive the screws 15 and 24 for the same purpose as set forth in the preferred form. 80

From the foregoing description, it will be seen that I have provided a simple mounting for the armature of a loud speaker unit, in which the anchorage therefor is embedded in a lead base or other non-sounding material 85 whereby the base is prevented from receiving any of the vibrations from the armature during vibration of the same. This structure prevents any distortion in the sound produced and which is present in loud speakers now in use. This invention assures a reproduction of clear and natural tones. 90

While I have described what I deem to be the most desirable embodiment of my invention, it is obvious that many of the details 95 may be varied without in any way departing from the spirit of my invention, and I therefore do not limit myself to the exact details of construction herein set forth nor to anything less than the whole of my invention limited only by the appended claims. 100

What is claimed as new is:—

1. In a loud speaker unit having an armature, a base of non-sounding metal, and an anchor member embedded in said base to 105 which said armature is fixedly connected.
2. In a loud speaker unit having an armature, a lead base, an anchor member embedded

in said lead base, and a removable element engagable with said anchor member for securing said armature to said base.

3. In a loud speaker unit having an armature, a lead base, an anchor member embedded in said lead base and having a threaded bore therein, and a screw passing through said armature and co-acting with said threaded bore for securing said armature against said 10 lead base.

4. In a loud speaker unit having an armature, a lead base, an elongated anchor member embedded in said lead base, a screw pass-

ing through said armature and into said anchor member, and an adjusting screw threaded in said anchor member and engageable with said armature.

5. In a loud speaker unit having an armature, a metal base, an anchor member embedded in said base, and a removable screw 20 threaded to said base for securing said armature thereto.

In testimony whereof I hereby affix my signature.

ALFRED HERSCHEL.
